UNITED STATES PATENT OFFICE.

ARCHIBALD McCALLUM, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,646, dated March 12, 1872.

Specification describing a new and original Design for Carpets, invented by ARCHIBALD McCALLUM, of Halifax, in the county of York, England.

The accompanying drawing represents my new design.

The same consists of a peculiar new outline of a shield-like figure, A, and also of an oval figure, B, contained within a scalloped border, C, and ornamented as shown.

I claim as my invention—
The design for a carpet, containing the shield A, figure B, and border C, as shown.
ARCHIBALD McCALLUM.
